UNITED STATES PATENT OFFICE.

WEBSTER J. DALY, OF LOS ANGELES, CALIFORNIA.

AUTOMATIC SYRINGE FILLER.

1,408,272.

Specification of Letters Patent. Patented Feb. 28, 1922.

Application filed March 3, 1920. Serial No. 362,955.

To all whom it may concern:

Be it known that I, WEBSTER J. DALY, citizen of the United States, residing at Los Angeles, in the county of Los Angeles and State of California, have invented certain new and useful Improvements in Automatic Syringe Fillers; and I do hereby declare the following to be a full, clear, and exact description of the invention, such as will enable others skilled in the art to which it appertains to make and use the same.

This invention relates to the transfer of liquid from a reservoir to a syringe or the like. It comprises a liquid trapping reservoir having a filling well controlled by a valve seated by pressure from within the reservoir but adapted to be unseated by pressure from without. In the embodiment illustrated and described the valve is provided with a tubular valve stem extending to the exterior of the reservoir through which the liquid is dispensed and charged into a syringe.

The object of the invention is to facilitate the charging of syringes from a storage container without waste of liquid or substantial exposure of the liquid to the atmosphere. The particular use contemplated is the charging of syringes with medicinal fluids. The accompanying description and drawings disclose the invention in the best embodiment at this time known to me.

In the drawings:

Figure 1 is a top plan view of the invention;

Figure 2 is a vertical section in the line 2-2 of Figure 1;

Figure 3 is a vertical section on the line 3-3 of Figure 1, with the valve seated;

Figure 4 is a view of the same section as Figure 3 but with the valve unseated.

Like reference characters designate corresponding parts throughout the several views.

In the embodiment shown the body of the reservoir has a semi-cylindrical front face 1 and a flat rear surface 2 designed to rest against an upright wall. Laterally projecting ears 3 are perforated at 4 through which screws or other suitable fasteners may be inserted to sustain the reservoir on a wall.

In the lower portion of the body is a chamber 5 closed at the bottom by a threaded closure 6, the joint being made fluid tight by a gasket 7 fitted between the flange 8 of the closure and the bottom of the body of

the reservoir. The closure 6 has a depression 9 in its inner surface adapted to form a seat for the spring 22.

An orifice or channel 10 extends from the chamber 5 through the upper wall of the body. A port 11 connects the lower part of the chamber 5 with the vertical inlet conduit 12, which terminates in a nipple or tubular connector 13 projecting above the top of the reservoir body.

The channel or orifice 10 is controlled by a valve held to its seat by pressure from within the reservoir. A hollow valve stem 14 is mounted so as to have a limited vertical movement in the port or channel 10 and fits piston-tight therein. A flange 15 limits the downward movement of the hollow stem 14. The lower end of stem 14 is closed or formed with a partition or bottom web 16 having a threaded central orifice 17. Just above the bottom 16 are a number of ports 18 in the side wall of the tubular stem 14. A flange or disc 19 of metal or other hard material is secured to the member 14 by a screw 20 engaging the threaded hole 17. Clamped firmly between the disc 19 and the lower end of the member 14 is a packing washer 21 of any suitable material such as leather, fibre, rubber or the like. A coil spring 22 seated in the depression 9 of closure 6 exerts pressure against the disc 19 to urge the valve to its closed position. When the gasket or washer 21 bears against the upper wall of chamber 5 as illustrated in Figures 2 and 3 no liquid can pass through the ports 18. When the valve is depressed as illustrated in Figure 4 liquid may pass through ports 18 and upward through the tubular member 14 which lines the channel 10.

Hydrostatic pressure may be maintained in the conduit 12 through any suitable connection with a vessel containing a supply of the desired liquid at a suitable elevation. The nipple 13 provides a convenient means of connection for a supply tube or other means for conducting liquid into the reservoir 5.

In Figures 3 and 4 the nozzle of a syringe 105 S is delineated by a broken line. The upper end of the tubular member 14 is circular and the syringe tip illustrated is conoidal and of yieldable material, thus fitting snugly and fluid tight in the end of the member 14. Pressing downward the syringe tip opens the ports 18, and liquid, such as a

medicinal solution, flows through the ports 18 and fills the hollow member 14. The expandible fluid receiving chamber of the syringe should at this time be contracted. 5 If now the chamber be expanded a charge will be drawn into the syringe. When the syringe tip is lifted from the member 14, the valve immediately closes and confines the medicated or other liquid so that none 10 escapes.

15 The invention is particularly useful in hospitals and for medicinal and surgical practitioners. The supply of medicated liquid may be kept free from contamination, and a syringe may be filled quickly without waste of the medicament.

20 In case the syringe to be filled has a hard unyielding tip, it might be found desirable to make the edge of the upper end of the hollow valve stem of yielding material as 25 by securing a gasket thereto as indicated at 23.

25 The hollow stem 14, it will be seen, constitutes a filling well adapted to receive the liquid to be taken up by the syringe when the valve is depressed.

30 The closure 6 is of a size to admit the valve and spring to be readily assembled in the process of manufacture of the device.

35 Having described my invention in the embodiment best known to me what I claim and desire to secure by Letters Patent is as follows:

40 1. A syringe filling device consisting of a body having a reservoir therein, a well extending from the reservoir through the top of said body, said well being of a size to receive the nozzle of a syringe within it, and a vertical liquid feed conduit in the body having its lower end communicating with said reservoir; and a valve disposed so as to close communication between the reservoir and the well in response to pressure exerted upward from the well, said 45 valve permitting liquid to flow from the reservoir into the well when it is depressed.

2. In a syringe filling device, a body having a reservoir, an orifice extending from the reservoir to the top of the body, a valve comprising a tubular stem fitting said orifice and a flange at the lower end of said stem adapted to seat fluid-tight under upward pressure, said stem having a lateral port therethrough adjacent to and above the flange, said stem having one end projecting normally above the top wall of the reservoir and a stop flange on the top of said stem to limit the downward movement of said valve by contact with the top of said body. 50 55 60

3. In a syringe filling device, a body having a reservoir, an orifice extending from the reservoir to the top of the body; a valve comprising a tubular stem fitting said orifice and a flange at the lower end of said stem adapted to seat fluid-tight under upward pressure, said stem having a lateral port therethrough adjacent to and above the flange and being imperforate above said port, and an internal packing gasket at 70 the upper end of said stem projecting slightly inward so as to make a fluid-tight joint between it and the nozzle of a syringe inserted into said stem. 65 75

4. A syringe filling device comprising a substantially semicylindrical body having a flat rear wall with projecting flanges adapted to be secured against a vertical wall, said body having a syringe-filling well in its top wall and a reservoir adapted to be placed in communication therewith, a valve normally closing the ports between the well and said reservoir, said valve adapted to be opened by downward pressure thereon, a vertical conduit in said body between the filling well and the flat wall, said conduit being in communication with the lower part of said reservoir and adapted to be connected with a source of hydrostatic pressure. 80 85 90

In testimony whereof I affix my signature.

WEBSTER J. DALY.
